UNITED STATES PATENT OFFICE.

EDWARD A. TUTTLE, OF NEW YORK, N. Y.; ARTHUR C. TUTTLE AND HERBERT B. TUTTLE EXECUTORS OF SAID EDWARD A. TUTTLE, DECEASED.

HOT-AIR HEATING-FURNACE.

SPECIFICATION forming part of Letters Patent No. 757,520, dated April 19, 1904.

Application filed September 26, 1900. Renewed January 13, 1904. Serial No. 188,923. (No model.)

To all whom it may concern:

Be it known that I, EDWARD A. TUTTLE, a citizen of the United States of America, and a resident of New York city, county and State of New York, have invented certain new and useful Improvements in Hot-Air Heating-Furnaces, of which the following is a specification.

My invention relates to hot-air heating-furnaces of the kind usually set in brick inclosures for causing circulation of air for heating about the fire-box to be heated and being of quadrilateral form; and it comprises improvements in the construction of the fire-box to facilitate simplicity and cheapness of construction, effective and reliable self-feeding and regular combustion of the fuel, and also effective communication of the air for transmitting the heat, with the heating-surfaces of the fire-box to be heated, as hereinafter described, reference being made to the accompanying drawings, in which—

Figure 1 represents a central sectional elevation of my improved furnace. Fig. 2 represents a transverse vertical section on line 2 of Fig. 1. Fig. 3 represents a horizontal section on line 3 3 of Fig. 1.

The fire-box A is formed of two equal and like cast-metal parts of practically pan shape with lateral extension-gaps *a* for a self-feeding magazine, like gaps *b* for access to the ash-pit, and holes *c* for escape of the gases of combustion, said parts adapted to close together at the edges *c* and be bolted fast through lugs *d*, said edges to be planed true, and thus be closed gas-tight. The structure thus produced is set up edgewise—that is, with the joint in the central vertical plane—the magazine being over the ash-port and suitably inclined for gravitation of the coal as the mass below is consumed.

The coal-magazine is provided with a door *f* for closing while the furnace is working. The ash-port is also provided with a door, as *g*; but it will have the usual air-inlet opening and regulating-valve for controlling the draft. A sloping grate *j* is arranged in line with the bottom of the coal-magazine for re-

ceiving the coal therefrom, said grate terminating a little short of the rear end of the ash-pit and also a short distance above the bottom of the ash-pit and leaving an open throat for the settling of the ashes, cinders, and clinker down into the ash-pit as the collections are raked forward from time to time, said throat being in such proximity to the bottom of the ash-pit that kindling placed under the throat to begin with will choke the throat and obstruct the fall of the coal subsequently charged into the magazine and will occupy the most favorable relation to the coal for starting the fire, and as the kindling burns away the coal will settle down in contact with the fire for thorough ignition, and for a time the fire will be to a considerable extent in and below the throat; but as the ashes accumulate the body of the fire will be higher and the ashes will serve as a regulator, according as they are raked away from time to time.

The fire-box is wider than the magazine and the grate, as seen in Figs. 2 and 3, and in the recesses of the sides of the fire-box within the magazine side plates *h* are set up to support refractory material for the protection of the side plates of the fire-box from excessive heat, said side plates being inclined correspondingly with the inclination of the grate and reaching from the front plate of the fire-box backward and downward to the back plate, which is preferably formed on an inward incline *l* from about the height of the side plates or a little higher to the top of the ash-pit. As this part of the back plate will usually be protected by ashes and cinders from excessive heat, refractory lining of it will probably not be needed; but such lining may be applied, if desired.

The height of the side plates *h* will be a little more than the depth of the fire-bed. They are flanged, as at *m*, on the insides to facilitate holding the clay or other lining of refractory material, said flanges preferably ranging lengthwise of the plates. These side plates are also flanged or ribbed on the back crosswise, as shown at *n*, to offset the plates a little from the side plates of the fire-box and form flue-spaces *o* in communication with the

air-space under the fire-grate to supply air above the fire-bed, and dampers p are located above these flues to graduate the supply of air as required, said dampers having their

5 pivot-rods q extending upward through the front of the furnace suitably for manipulating them. These side plates have their ends beveled correspondingly with their inclinations relatively to the side walls of the fire-
10 box on which they rest, and thus are supported in their positions, being insertible and removable at will without the manipulation of any fastening devices, except it may be preferred to use a couple of stove-bolts, as q , to
15 prevent them from toppling over.

The grate j is detachably supported on lugs s , projecting inward from the lower flanges m of these side plates, with the lower cross-bar t of the grate extended into notches u of said
20 flanges to prevent the grate from slipping downward. By entering the grate through the magazine engaging the projecting ends of bar t with the notches u and dropping the upper end of the grate onto its bearing-lugs s
25 the grate will be readily placed in position, and it is obvious that it may be as readily removed by the reverse of these movements. The lining of the side plates may have to be notched a little at the notches u of the lower
30 flanges m to facilitate the engagement of the said projecting ends of bar t with said notches u .

The fire-box is placed in a brick inclosure v , in which it is supported on abutments w ,
35 and in the front wall where the ash-port and magazine project through it with intervening space x for causing effective contact of the air for transmitting the heat with the plates of the fire-box for being heated. The air enters to this space x , hereinafter called the "secondary" air-chamber, through inlets y of the inclosure v and is conducted away from the top, as usual, through conductors z . Another
40 brick inclosure 2 surrounds three sides of inclosure v and includes an air-space 3 , hereinafter called the "primary" air-chamber, into which the air for heating is received at 4 , wherefrom it passes along the walls of inclosure v to the inlet-passages y and is heated
45 thereby to a considerable extent before entering the hot spaces of the secondary air-chamber x next to the fire-box. The air in primary chamber 3 is also further heated by flues
50 located therein and receiving the hot products from the fire-box through pipes 6 , communicating with the fire-box at e and passing through walls v . The flues 5 discharge through branch pipes 7 into the smoke-pipe 8 , which connects with the chimney, as usual, for discharge into the air, said pipe 8 being located in the cold-air inlet 4 for giving up as much as possible of the heat of the waste products before escaping.

The flues are made wide and shallow, as represented in Fig. 2, for affording large area of

surface exposure proportionately to the volume capacity for economy in heating the air by contact, which is known to be the essential way, as it does not absorb radiant heat.

The smoke-flues are arranged horizontally 70 along the sides of the fire-box in primary air-chamber 3 , and the discharge-pipe enters the chimney at about the same level, and the incoming cold air is carried along in the opposite direction, first coming in contact with the out-going end of the smoke-pipe. 75

Instead of a smoke-pipe 6 at each side of the fire-box discharging into the chimney at the back the pipe 6 of one side may be omitted, and a single flue connecting with the one pipe 80 may be extended around the three sides of the primary chamber into the chimney located at the side of the fire-box opposite the remaining pipe 6 .

Baffle-plates 9 in chamber 3 under flues 85 cause the incoming air to flow along and in contact with the flues their entire length before escaping from said chamber 3 into chamber x , and thus insure more effective heating of the air. 90

Some of the advantages of my improved furnace may be stated as follows:

The inclined fire-bed and coal-magazine at the upper end of the bed allow a constant self-feed of the fuel into the end of the fire-box, 95 never overcharging and choking the fire, but always maintaining a lively and even fire and constant maximum radiation of heat to the plates of the fire-box. The livelier and more uniform fire thus affords more heat from a 100 smaller area of fire-bed, and more heat is obtained from the coal consumed, because of the more perfect combustion of the gases evolved from the coal, a large proportion of which it is known goes to waste whenever the fire is 105 choked and combustion checked by charging the air with fresh supplies of coal from time to time.

The regulated passage for supplying heated air to the surface of the fire-bed by causing it 110 to pass up along the hot sides of the fire-bed is a simple and effective contrivance for promoting better combustion above the fire-bed.

The separate primary air-chamber surrounding the inner or secondary air-chamber 115 provides larger area of contact-surface in an economical and compact form, and the arrangement of the smoke-flues in said primary chamber for parting with the heat of the smoke before entering the chimney and at the same 120 time raising the temperature of the incoming cold air in a thorough manner before entering the secondary air-chamber is an efficient means of promoting even and regular currents of the air to be heated, thus preventing 125 unequal and imperfect heating and avoiding obstructive counter-currents inseparable from the introduction of the coldest air directly into one main heating air-chamber of a furnace.

As the air must be heated by contact, it is 130

important that a large amount of contact-surface be brought to bear to raise the temperature from, say, zero or thereabout to 70° Fahrenheit, which is frequently the difference between the outside air and the required temperature of one room.

With limited heating-surface the pressure from the outside tends to force the air through the furnace without adequately and evenly heating it, so that while the direct radiation from the surface of the fire-bed upon a thermometer might show 200° or even 250° the air flowing into the rooms through the registers would not be even 80° or 90°. This is the reason the ordinary furnace, with a single heating-chamber and its immense area of coal-bed, fails to give reasonable returns of heat for its large consumption of fuel.

What I claim as my invention is—

20 1. The fire-box consisting of two like pan-shaped parts having ash-port and magazine-extension gaps, and smoke outlet or outlets, said parts joined and clamped together at the edges and set up with the meeting joint in the vertical center plane, the magazine being above the ash-port and suitably inclined for self-feeding the coal.

25 2. The fire-box consisting of two like pan-shaped parts having ash-port and magazine-extension gaps, and smoke outlet or outlets, said parts joined and clamped together at the edges and set up with the meeting edges in the vertical central plane, the magazine being above the ash-port and suitably inclined for self or end feeding, and the inclined grate in combination and coincident therewith.

30 3. The fire-box consisting of two like pan-shaped parts having ash-port and magazine-extension gaps, and smoke outlet or outlets, said parts joined and clamped together at the edges and set up with the meeting joint in the vertical central plane, the magazine being above the ash-port and suitably inclined for self or end feeding; the inclined grate in combination and coincident therewith, and a throat-space at the lower extremity of the grate, opening into the ash-pit.

35 4. The fire-box consisting of two like pan-shaped parts having ash-port and magazine-extension gaps, and smoke outlet or outlets, said parts joined and clamped together at the edges and set up with the meeting joint in the vertical central plane, the magazine being above the ash-port and suitably inclined for self-feeding; the inclined grate in combination and coincident therewith, a throat-space at the lower extremity of the grate opening into the ash-pit, and the protective plates at the sides of the fire-grate.

40 5. The fire-box consisting of two like pan-shaped parts having ash-port and magazine-extension gaps, and smoke outlet or outlets, said parts joined and clamped together at the edges, and set up with the meeting joint in the central vertical plane, the magazine being

above the ash-port and suitably inclined for self-feeding; the inclined grate in combination and coincident therewith, a throat-space at the lower extremity of the grate opening into the ash-pit, the composite protective plates at the 70 sides of the fire-grate, said plate having the ribbed back offsetting it from the fire-box plates and forming air-ducts supplying air over the fire-bed and valves controlling said ducts.

75 6. The combination with the fire-box, inclined self-feeding magazine and fire-grate, of the quadrilateral secondary air-chamber, primary air-chamber of like form inclosing three sides of the secondary air-chamber, horizontal smoke-flues located in the three divisions of said former chamber, cold-air inlet to said primary chamber, and air-passages from the primary air-chamber to the secondary air-chamber through the lower part and opposite 80 sides of the wall of the latter chamber, the hot-air outlets being at the top of the secondary air-chamber.

7. The combination with the fire-box, inclined self-feeding magazine and fire-grate, of 90 the quadrilateral secondary air-chamber, primary air-chamber of like form surrounding three sides of the secondary air-chamber, horizontal smoke-flues located in the three divisions of said chamber, and connected with 95 the fire-box through the inclosure of the secondary air-chamber, inlet for cold air to the primary air-chamber, discharge-pipe of the smoke-flues extended through said cold-air inlet, and air-inlets from the primary air-chamber to the secondary air-chamber through the opposite sides of the wall of said latter chamber at the base.

8. The combination with the inclined fire-bed and magazine, of vertical air-passages behind and intermediate of the side walls of the fire-bed, and the shell of the fire-box from the ash-pit to the surface of the fire-bed, and valves lying over the issues of said passages at their upper ends, said valves having their 105 pivot-rods extending upward through the front wall of the furnace, said passages being formed in said side walls.

9. A hot-air self-feeding furnace having the quadrilateral primary and second air-heating 115 chambers, the former surrounding three sides of the latter, with cold-air inlet to the primary chamber, and inlets from opposite sides of the primary chamber to the secondary chamber and the baffle-plate, arranged to 120 cause the air to traverse the primary chamber from back to front before reaching the inlets to the secondary chamber.

10. The combination with the fire-box, quadrilateral inclosure therefor, primary air-chamber and inclosure therefor surrounding three sides of the secondary air-chamber inclosure, horizontal smoke-flues located in said primary chamber, and connected with the fire-box through the inclosure of the second- 130

ary air-chamber, inlet for cold air to the primary chamber, discharge-pipe of the smoke-flues extended through said cold-air inlet, air-inlets from the primary air-chamber to the 5 secondary air-chamber through the wall of said latter chamber at the base, and the baffle-plates in the primary chamber causing the cold air to traverse the length of the smoke-

flues before reaching the inlets from the primary chamber to the secondary chamber.

Signed at New York city this 7th day of July, 1900.

EDWARD A. TUTTLE.
